DESIGN FOR COMBINED ROSE AND ESCUTCHEON.

Design No. 11,213, dated May 27, 1879

UNITED STATES PATENT OFFICE

GEORGE S. BARKENTIN, OF HARTFORD, CONNECTICUT, ASSIGNOR TO P. & F. CORBIN, OF SAME PLACE.

DESIGN FOR COMBINED ROSE AND ESCUTCHEON.

Specification forming part of Design No. 11,213, dated May 27, 1879; application filed May 3, 1879.
[Term of patent 7 years.]

To all whom it may concern:

Be it known that I, GEORGE SLATER BARKENTIN, of the city of Hartford, in the county of Hartford and State of Connecticut, have invented or produced a new and original Design for Rose and Escutcheon, of which the following is a full, clear, and exact description, reference being had to the accompanying engraving, making part of this specification.

The general outline of the rose and escutcheon A and drop B are sufficiently shown in the accompanying engraving.

The borders *a a* are composed of the zigzag bands, each upper division inclosing a pointed leaf, and each lower division a small sunken leaflet.

The border *b* is composed of semicircular bands inclosing conventional leaf ornaments, between which are husks, all in relief upon a sunken dotted ground.

The thimble *c* is encircled by a border, *d*, composed of incised lines and dentals inclosing a circle of quarterfoils in relief.

Upon each side of the panel *e* are perpendicular flutes *f f*, intersected by rosettes *g g*. Within the panels *h* and *i* are foliated ornaments in relief, as shown.

The design of the drop B consists in its peculiar shape and ornamentation. Upon the upper part is a small leaf ornament within a sunken panel, followed by flutes intersected by a rosette, and terminating with a segmental band, upon which are incised lines and dentals.

I claim as my invention—

1. In a rose and escutcheon, the design of the general outline of the plate and drop, substantially as shown.

2. In a rose and escutcheon, the design for the face, consisting of the borders *a*, *a*, *b*, and *d*, the perpendicular flutes *f f*, intersected by rosettes *g g*, and the panels *h* and *i*, combined and arranged substantially as shown and described.

3. In a rose and escutcheon, the design for the face of the drop B, consisting of the panel ornament followed by flutes and rosette, and terminating with the segmental band, substantially as shown and described.

GEORGE SLATER BARKENTIN.
